UNITED STATES PATENT OFFICE.

GUSTAVE C. KOSIAN, OF ROCKFORD, ILLINOIS, ASSIGNOR TO ROCKFORD MALLEABLE IRON WORKS, OF ROCKFORD, ILLINOIS, A CORPORATION OF ILLINOIS.

SAND-BLAST APPARATUS.

Application filed January 11, 1923. Serial No. 611,956.

This invention pertains in general to cleaning by sand and other abrasives, and has more particular reference to sand blast apparatus in which the articles to be cleaned are tumbled in a barrel and subjected to the sand blast.

Sand blast apparatus heretofore provided and now in commercial use, has been characterized by support of the tumbling barrel 10 drum directly on rollers, overhead sand hoppers and endless chain and bucket conveyors for elevating the sand to the hoppers, all of which have been inherently cumbersome and have imposed a great deal of friction, and 15 the consequent increased power required for driving. Furthermore, because of these operating parts being exposed to the sand, scale and other foreign matter, they are comparatively short lived and continually requiring 20 repair, with the result that the cost of maintenance and operation is comparatively high.

One of the primary objects of the present invention is to obviate the objections mentioned by the provision of generally improved sand blast apparatus, which will be 25 comparatively long lived and will require a minimum amount of power for operation and low cost for maintenance. Another object is therefore to effect economy in sand blasting 30 castings and the like.

In furtherance of the foregoing general objects, my invention contemplates the provision of a novel tumbling barrel and mounting therefor, the barrel being characterized 35 by its undulated drum structure, and its mounting by trunnions supported on rollers which with the trunnions are housed in oil tight and dust-proof casings. The undulations of the drum function to tumble or turn 40 the castings most effectively to insure the desired presentation of all sides to the sand blast. The novel mounting of the tumbling barrel is a very important factor in my invention in promoting sand blast efficiency as it 45 not only provides an ideal mounting for the heavy barrel adapted for long service without attention, but it also provides for a most effective arrangement of the means for delivering the sand blast.

Said mounting also allows the use of sand blast delivery means of novel construction, and in this regard my invention contemplates the provision of an improved sand blast delivery means of the injector type, which will 50 be explained more fully hereinafter.

Another object is to improve the means for handling the sand so that it may be most efficiently moved in its cycle.

Other objects and attendant advantages will be appreciated by those skilled in this 60 art as the invention becomes better understood by reference to the following description when considered in connection with the accompanying drawings, in which—

Figure 1 is a front view of a sand blast machine embodying my invention;

Fig. 2 is a side elevation of the machine;

Fig. 3 is a vertical section through the machine taken substantially on the line 3—3 of Fig. 2;

Fig. 4 is a vertical section taken substantially on the line 4—4 of Fig. 3;

Figs. 5 and 6 are sections taken on the lines 5—5 and 6—6 respectively, of Fig. 3;

Figs. 7 and 8 are top views of the lower 75 sections of the trunnion-supporting casings at the right and left hand ends of the machine, respectively, viewing Fig. 3;

Fig. 9 is a section taken on the line 9—9 of Fig. 8;

Fig. 10 is a perspective view of the charging plate forming part of the tumbling barrel drum;

Fig. 11 is a detail section through the sand blast injector taken on the line 11—11 of 85 Fig. 3; and

Fig. 12 is a top view of the injector casting and sand blast nozzle co-planar with said injector section.

Tumbling barrel.

The tumbling barrel is composed, generally stated, of opposed heads 15 and 16 joined by drum plates 17 and carried by hollow trunnions 18 and 19, respectively. In view of the 95 large dimensions and heavy proportions of these parts, I prefer that they shall be made separately by casting. Each head 15 and 16 is seated on a shoulder 21 at the inner end of its respective trunnion and is secured by bolts 22 to a trunnion flange 23. Said heads each have an annular flange 24 to which complementary ends of the drum plates 17 are secured by bolts 25. These drum plates intermediate the heads are shaped to provide undulations of 100 substantial depth, as clearly shown in Figs. 3 and 4, the undulations of each plate matching those of the adjoining plates, providing an endless symmetrical internal undulation in the plane of rotation. The drum plates 105 110

are, therefore, segmental as shown in Fig. 4; and suitable openings 26 are provided between the plates to permit escape of the sand. These openings or perforations may be 5 formed by drilling or by allowing interstices between the plates. The undulated internal wall of the drum functions upon rotation to positively carry the mass of castings with the drum so that the leading or upper end of the 10 mass will be raised to a comparatively high level and the castings at such end will roll back down over the mass. Thus, all of the castings travel in a cycle in which they are periodically raised to the high end of the 15 mass and roll down over it. As will be explained hereinafter, one or more continuous blasts of sand or other abrasive material are delivered against both the mass of castings and said rolling castings. This blast is 20 preferably so arranged as to strike the rolling castings with the greatest force, and since the castings are continually turning, the entire surface of each will be inevitably presented at different times to the sand blast and thus 25 effectively cleaned. The blast also strikes the mass of castings beneath the rolling castings and functions to loosen the sand and scale and to clean these also before the force of the blast is spent. This spent sand gravitates to the lowest points in the troughs or 30 pockets formed by the undulations and readily escape through the openings in the drum. It will be further observed that the series of troughs or pockets formed by the undulatory 35 shape of the wall, not only positively moves the mass of castings with the drum but causes small masses of castings at the upper end to roll down over the mass, although at all times there are castings in motion, rolling down 40 the mass and breaking away at irregular intervals from the top thereof. However, the castings in the pockets or troughs formed by the undulatory wall will be carried to a higher level than otherwise, and said small masses 45 raised to this higher level but not above and separated from the main mass, will have greater momentum when rolling down and will present a greater number of square inches of surface to the sand blast per unit of 50 time than if rolling slowly from a lower level. This hastens the cleaning action and promotes greater efficiency in a machine of this class.

One of the drum plates 17', best shown in 55 Fig. 10, at present double the width of the plates 17, has a charging opening 27 therethrough, and seats 28 at the end of such opening for the reception of a charging door 29. This charging door, it will be noted, has undulations complementary to those on the plate 17', so that the continuity in the shape of the internal wall is not broken. The charging door is preferably bodily removable from the drum for charging and unloading, and I prefer to employ a crane (not shown) adapted 60

to connect to the eye-bolt 31 for handling the heavy door. Clamping blocks 32 disposed in the outside hollows of the plate 17' are adapted for rigidly clamping the charging door to the seats 28. A bolt 25' passing 70 through a slot 33 in each clamping block and through the flange 34 of the plate 17', is threaded into the flange 24 of the adjacent head 15, thereby serving to tighten the clamps and also to hold the plate 17' in position. It 75 will be manifest that when the bolts 25' are loosened, the clamping blocks 32 may be slid outwardly from their clamped position shown in Figs. 1 and 10, thereby permitting removal of the charging door, and that by reversal of these operations the charging door may be rigidly clamped in closed position. The charging opening may obviously traverse the width of one or more drum plates, but in order to insure greater rigidity and 85 sturdiness of construction, I prefer to form the opening in a single plate and to reinforce the longitudinal edges by ribs 35, as shown.

The foregoing construction is especially 90 advantageous in that any of the drum plates may be removed without dismantling the entire barrel or removing it from its bearings, thus permitting quick and easy replacement of drum plates when necessary.

Tumbling barrel mounting and drive. 95

Each trunnion 18 and 19 is supported on a pair of rollers 36, best shown in Fig. 6, which in turn are mounted on anti-friction rollers 37 on a supporting shaft 38. The rollers 36 for the trunnion 18 are supported in the lower section 39 of a casing and the rollers for the trunnion 19 in a lower casing section 41. Each of these casing sections seats upon and is secured by bolts 42 to a side housing designated generally by 43. These side housings are preferably heavy castings forming the main supporting structure for the tumbling barrel and also providing a side frame and retaining wall for the sand hopper which will 100 be described later. Each lower casing section is hung in a recess 44 as shown in Fig. 6, and is shaped to provide an inclosure about the lower half of its respective trunnion, and also to serve as an oil reservoir. Upper cas- 105 ing sections 45 and 46 rest upon the lower cas- 110 ing sections 39 and 41 respectively, and are shaped to inclose the upper half of the respective trunnions. Said casings are suitably se- 115 cured together as by bolts. Packing is pro- 120 vided for all joints, thru which access may be had to the compartment inclosed by said casing sections, thus making the trunnion bearings dust proof. I prefer to groove these 125 joints as indicated by 47 and to fill said grooves with heavy felt packing 48. It will be observed viewing Figs. 3, 7, 8 and 9 that this packing circumscribes each trunnion at its inner and outer ends, so that its bearing 130 surface 49 is disposed wholly within the in-

130

closed, packed-joint compartment, and that the meeting edges between the upper and lower sections are likewise packed. Each lower casing section provides an oil well or reservoir 51 adapted to carry lubricant in which the rollers 36 dip.

The casing for the trunnion 18 also has an enlarged extension 50 inclosing a spur gear 52 and driving pinion 53, the former fixed 10 to said trunnion and the latter to a shaft 54 journaled in a bearing in said casing. The compartment provided by the casing portion 50 also serves as a lubricant container for the gearing. Any suitable means may be employed for driving the shaft 54, as for example a belt 55 and pulley 56, the latter having a bevel gear connection, not shown, with the shaft 54. This means serves to revolve the tumbling drum slowly at a uniform speed, 20 and may be started and stopped at will to properly position the charging door in front of the machine.

From the foregoing it will be seen that the trunnions are revolvably mounted on anti-friction roller bearings, which together with the drive gearing, are entirely inclosed in dust proof casings. This mounting is very efficient for sand blast machines and will not be affected by the sand and dust which is 30 present to a greater or less extent during operation, and which has been very destructive to the mountings of prior machines.

Sand blast injector.

35 Means is provided in each hollow trunnion for delivering a blast of sand into the tumbling barrel. Inasmuch as the construction of each sand blast delivery means is similar, a description of one will suffice, similar reference numerals being applied to duplicate parts.

While my invention contemplates in its broadest aspect the use of any means for delivering a sand blast through each trunnion, 45 I prefer to employ and have provided as an object of the invention, an improved means of the injector type. This means comprises a casting 57 shown in Figs. 3, 11 and 12, shaped to provide a mixing chamber 58, the major axis of which when supported in position as will be presently described is inclined downwardly and passes diagonally through the hollow trunnion. This casting also provides at the upper end of said chamber, a pair of air nozzle openings 59, and at 50 the lower end a blast nozzle opening 61, both of which are co-planar with said major axis of the mixing chamber. Said casting is further shaped to provide a sand inlet or feed opening 62 on its under side intermediate said openings 59 and 61 and a downwardly reaching sand-feed pipe 63 terminating beyond the end of the trunnion. Air is delivered under high pressure to the mixing chamber 58 through two nozzles, each comprising

a body 64 threaded in an opening 59 and having a jet 65 disposed within the mixing chamber and an angular head 60 at the exterior thereof, terminating in a coupling end 67 to which an air pressure hose 68 is attached. 70 Each jet 65 is covered throughout its length by a rubber sheath 69 for preventing abrasion of the jet by the sand. A sand blast nozzle 71 having a tapered end 72 secured in the opening 61 by suitable means, such as set 75 screws 73, is provided with two parallel delivery passages 74 co-axial with the jets 65. The delivery end of the blast nozzle is directed into the tumbling drum through an opening in a stationary head 75, which closes the inner end of the hollow trunnion and is attached by a bolt 76 to a bracket extension 77 of the injector casting. This casting has also an outer bracket extension 78 terminating in a head 79 secured by bolts 81 to a bracket 82, 85 which is bolted at its ends to the lower section of the trunnion casing. The bolts 81 pass through arcuate slots 83 concentric with the axis of the tumbling barrel. This construction permits adjustment of the injector 90 bracket about said axis for the purpose of setting the delivery of the sand blast at any point in an arc within the lower portion of the barrel, thereby enabling the sand blast to be most effectively used for castings of different sizes and shapes. A hose 84 connects the lower end of the sand feed passage 63 to a sand hopper, which will be presently described.

Housing and hopper structure.

The side housings 43 mentioned above, preferably in the form of heavy castings for carrying the weight of the tumbling barrel and appurtenances, serve as a lateral support 105 for the sand hoppers 85 beneath the tumbling barrel. In the present machine sheet metal plates 86 close the large perforations in the side housings. Said side housings are held in rigid relative relation by upper and lower 110 cross bars 87 and 88. Channel bars 89 likewise connecting said side housings, support a scale screen 91 which reaches from one side housing to the other and from the rear wall 92 to the front of the machine and is inclined downwardly. This screen allows the falling sand to pass through to the hoppers but intercepts any large particles of scale and other foreign matter. The upper edges of the front and rear walls 93 and 94 are also attached to the channel bars 89 and converge downwardly. The inner wall 95 of each hopper is also inclined downwardly toward the adjacent side housing. Each hopper is thus restricted practically to a point at its lower 125 end, and has an outlet 96 in such end through which the sand is adapted to flow into an open-top pocket 97 formed by a bracket 98 attached to the outer side of the adjacent side housing. Each suction hose 84 connects 130

at its lower end to a pipe 99 emanating from said pocket. A swinging gate valve 101 is adapted to control the delivery of sand through the opening 96 into the pocket 97.

5 A hood 102 incloses the upper half of the tumbling barrel, except for the front which is adapted to be closed by any suitable closure, such for example as a flexible roll door 103. The lower front of the machine, also 10 open, is adapted to be closed by suitable means such as swinging doors 104 indicated in Fig. 2. A pipe 105 connected to the top portion of the hood 102 leads to a suction fan, not shown, for drawing the dust-laden 15 air from the hood.

Operation.

The tumbling barrel will be stopped with the charging door at about the position shown 20 in Fig. 4 and there loaded with castings to about one-third capacity, that is, approximately to the level of the lower end of the stationary head 75. After the charging door has been locked in closed position, the tumbling barrel will be continuously revolved 25 at a speed commensurate with the size and shape of the castings, (which in many instances approximates three R. P. M.) in a clockwise direction viewing Fig. 4, causing 30 the castings to tumble in a mass indicated by the dotted line 106. In practice, the injector brackets are adjusted so that the blast is directed rearwardly so as to strike the mass of castings in a more central position than would 35 result from the vertical setting of said injector castings shown in the drawings. It will also be observed that in practice the level and inclination of the dotted line 106 indicating the top of the mass of castings and the quantity 40 thereof varies considerably according to the size, shape and material of the castings. In some cases the barrel may be loaded to a greater extent than shown, and the high or leading end of the mass will be higher than 45 shown and the angle of the top of the mass greater.

Air will be delivered from the jets 65 at a high velocity, creating a partial vacuum in the mixing chamber, which induces suction 50 in the sand feed passages 63—84 sufficient to raise the sand from the pockets 97, to the mixing chambers, from which it will be drawn into the air currents issuing from the jets 65 and expelled through the blast nozzles 55 at a high velocity. The sand blasts have a cleaning and abrading action, as are well understood in this art. After the impact, the sand sifts through the tumbling barrel and into the hoppers 85 in which it gravitates 60 to the lowest points and fills the pockets 97.

By reason of the arrangement of parts, the sand travels in a comparatively short cycle, which obviously promotes efficiency. Also 65 because of the comparatively small lift of the sand and slight frictional resistance to

its passage, comparatively low air pressure may be employed for obtaining a blast velocity sufficiently high for all practical purposes. The positioning of the blast injectors in the hollow trunnions is also a factor promoting compactness and accessibility of parts. In regard to the latter feature, it will be observed that in practice it is necessary to frequently inspect the nozzles, and this may be done conveniently with the present construction, especially when changing the blast nozzles 71, which become worn internally from the abrasion by the sand. The double feed nozzles allow maintenance of the desired velocity and high sand delivery volume with 70 comparatively low air pressure. By mounting the tumbling barrel in the manner disclosed herein, very little power is required for driving the barrel, and the bearings are of such a substantial character and so protected 75 as to possess unusual longevity.

The words "sand blast" are used in the specification and claims as meaning any abrading material delivered by air pressure or any other force for cleaning or finishing 80 the castings; and "castings" is used as meaning any part or article to be cleaned or finished by the sand blast, although in practice, these machines are primarily used for cleaning 85 castings only.

It is believed that the foregoing conveys a clear understanding of the objects prefaced above, and it will be evident to those skilled in the art that the principles disclosed herein are important factors in promoting blasting 90 efficiency, low cost of production of sand blast apparatus, and low cost of maintenance and operation thereof. It should be understood that while I have illustrated but a single working embodiment, many changes 95 might be made in the construction and arrangement without departing from the spirit and scope of the invention as expressed in the appended claims.

I claim:

1. Sand blast apparatus comprising a tumbling barrel having hollow trunnions, revolvably supported, a supporting part reaching across the outer end of each trunnion, means carried by each supporting part reaching inwardly and equipped at its inner end with a stationary head closing the passage between the interior of the tumbling barrel and the trunnion, and a sand blast nozzle carried by said means for delivering 100 a sand blast through said head.

2. Sand blast apparatus comprising a tumbling barrel having hollow trunnions, revolvably supported, a supporting part reaching across the outer end of each trunnion, means carried by each supporting part reaching inwardly and equipped at its inner end with a stationary head closing the passage between the interior of the tumbling barrel and the trunnion, a sand blast nozzle 110

carried by said means for delivering a sand blast through said head, and means for adjusting each nozzle-supporting part about a horizontally disposed axis for varying the 5 delivery of the sand blast with respect to the body of castings within the tumbling barrel.

3. In a sand blast machine, in combination, a barrel having hollow trunnions at its ends, bearings for the trunnions on which the barrel is supported for rotation, a stationary head located approximately in the plane of the end walls of the barrel and substantially closing the opening in each hollow trunnion, and a sand blast nozzle for delivering 10 through each stationary head into the barrel.

4. In a sand blast machine, in combination, a barrel having hollow trunnions at its ends, bearings for the trunnions on which the barrel is supported for rotation, a stationary head substantially closing the opening in each hollow trunnion, and means within the hollow of each trunnion for delivering a 15 blast of sand into the barrel through the interposed head and serving to support said head.

5. In a sand blast machine, in combination, a barrel having hollow trunnions at its ends, bearings for the trunnions on which the barrel is supported for rotation, a stationary head substantially closing the opening at the 20 inner end of each trunnion, a sand blast nozzle

for delivering through each stationary head into the barrel, and means supporting each stationary head and sand blast nozzle 25 exterior of the adjacent trunnion.

6. In a sand blast machine, in combination, a barrel having hollow trunnion ends, enclosed bearings for the trunnions on which the barrel is supported for rotation, a sand 30 blast gun in each hollow trunnion for directing a blast of sand into the barrel, intermeshing barrel driving gears within one of the bearing enclosures one of which gears being concentric with and fixed to the trunnion 35 thereon, means supporting each sand blast gun exterior to the adjacent bearing enclosure, and a stationary head substantially closing the opening through each hollow trunnion and through which the adjacent sand 40 blast gun discharges.

7. In a sand blast machine, a barrel having hollow trunnion ends, bearings for the trunnions on which the barrel is supported for rotation, means for rotating the barrel, means 45 providing a closure across the inner end of each hollow trunnion having a restricted opening for a sand blast nozzle, and independent sand blast delivery means located 50 within each hollow trunnion having a discharge nozzle for delivering a sand blast through the opening in the trunnion closure.

GUSTAVE C. KOSIAN.
